UNITED STATES PATENT OFFICE.

GEORGE C. HARLIN, OF STOCKTON, CALIFORNIA.

CAR-COUPLING.

SPECIFICATION forming part of Letters Patent No. 623,211, dated April 18, 1899.

Application filed December 2, 1898. Serial No. 698,079. (No model.)

To all whom it may concern:

Be it known that I, GEORGE C. HARLIN, a citizen of the United States of America, residing at Stockton, in the county of San Joaquin and State of California, have invented certain new and useful Improvements in Car-Couplers, of which the following is a specification, reference being had therein to the accompanying drawings.

10 This invention relates to improvements in car-couplers, and particularly to that class known as "automatic" couplers; and the object of the invention is to produce an arrow-head coupler which is automatically coupled, 15 and it consists in the provision of novel means whereby the parts are held in operative position against accidental displacement and whereby they (the said parts) may be released and swung out of operative position, that the 20 cars may be uncoupled.

A further object of the invention is to provide, in combination with the arrow-head coupler, a novel arrangement whereby the vertical-hook coupler may be swung into and 25 out of operative position when necessary for the purposes of the exchange of cars from road to road. Thus by my invention I acquire the direct pull of the arrow-head type under all possible conditions, while when it is impossible to employ the arrow-head type the vertical-hook coupler is speedily adjusted for use.

30 A further object of the invention is to provide means for guiding the parts into contact and making the parts strong, durable, and 35 efficient, while at the same time they are comparatively inexpensive.

With the above and other objects in view the invention consists in the details of construction and in the arrangement and combination of parts to be hereinafter more fully 40 set forth and specifically claimed.

In describing the invention in detail reference will be had to the accompanying drawings, forming part of this specification, wherein 45 like characters of reference denote corresponding parts in the several views, in which—

Figure 1 is a plan view looking at the bottom of my improved coupler applied to a car, with the parts broken away in places. Fig. 50 2 is a top plan view showing the mechanism which protrudes beyond the end of the car.

Fig. 3 is a central sectional view of the draw-head and draw-bar.

In the drawings, 1 denotes brackets which are attached to the car-beams, said brackets 55 having apertures to receive the ends of the follower-plates 2, said ends forming trunnions for supporting the draw-bar and allowing a swinging movement thereto. The draw-bar protrudes through the follower-plates and is 60 encircled by the usual spring 3 for absorbing the jar, &c. A sleeve 4 is formed with the front follower-plate and is provided with a depending portion 5, having an aperture to receive a bolt 6, which is spring-pressed and 65 arranged in a housing 7 of the draw-head extension 8, said draw-head extension encircling the draw-bar. Arranged on the draw-head extension is a lug 9, which is adapted to abut shoulders 10, formed by cutting away the 70 edge of the sleeve, for the purpose of limiting the rotation of the coupling-head.

The bolt 6 is withdrawn from engagement with the sleeve by the flexible connections 11, operating through a guide 12 on the draw-head extension and over the sheave-pulleys 13 on the transverse shaft 14, which shaft is so arranged as to be manipulated from the side of the car when it is desired to arrange the parts in operative or inoperative position, 80 it being necessary to rotate the said shaft in opposite directions to accomplish the two results, it being understood that when the coupler is locked in its operative position by the bolt the rotation of the shaft will exert a pull 85 on the flexible connection and that such pull will first withdraw the bolt from its engagement and when said bolt has reached its farthest backward limit further effort would be directed to the rotation of the coupling-head. 90

In conjunction with the mechanism just described I have provided a vertical-hook coupler which may be also used as a link-and-pin attachment, and in this arrangement I have an extension *a*, with a rounded inner 95 surface *b*, acting as a guide for the coupler of the opposite car, that the said coupler of the opposite car may be directed into operative position with relation to the adjacent coupler, and the link will lie in a slot (not shown) in 100 the end of said draw-head. On the casting with the extension and on the opposite side

thereof I arrange a sleeve or socket *c*, having a suitable internal shoulder *d*, against which a spring *e* abuts to provide a yielding connection for absorbing the jar, &c. The mouth 5 of the sleeve or socket has a flange *f* extending part way therearound, said flange having angular corners against which a lug *g* of the draw-bar *h* comes to limit the rotation of said draw-bar when thrown into or out of operative position, the coupling-head being held 10 in either of said positions by gravity. The draw-bar *h* is curved at approximately right-angles as it protrudes from the sleeve and terminates in a draw-head *i*, which draw-head, 15 with the guide, (heretofore described,) will afford an interlocking connection with the vertical-hook couplers now in use.

The draw-bar *h* is rotated by means of the beveled gear-wheels *A* and *B*, the former on 20 the draw-bar and the latter on a vertical shaft *C*, which takes motion from the shaft 14 through the worm-gear *D*.

When the link-and-pin connection is desired, the pin may be inserted in the aperture 25 *i'* of the draw-head *i*.

From the foregoing it will be seen that both forms are readily arranged for engagement and that one will not interfere with the other, although, as is well known, the vertical-hook 30 coupler does not have a central draft. Hence the pull is off center, and as it is necessary at times to exert a force of five thousand or six thousand pounds to effect a coupling of the couplers with vertical hooks the result is a 35 lateral force which causes great wear on the rails and car-wheels, and the road-bed itself is weakened by the jar incident to the operation of this class of couplers. Hence it is my object to use the arrow-head couplers whenever they can be substituted.

It will be noted in view of the foregoing that changes in the proportions and other details of construction may be resorted to, and yet the spirit of my invention will not be departed from.

Having fully described my invention, what I claim as new, and desire to secure by Letters Patent, is—

1. In a coupling, a draw-bar, a sleeve thereon having an apertured flange, a housing on the extension of the draw-bar, a spring-pressed pin in the housing adapted to be seated in the apertures of the flange, means for limiting the rotation of the draw-bar and arresting the 55 parts when the pin registers with one of the apertures, a flexible connection secured to the

end of the pin, and means for withdrawing the pin and rotating the draw-head at a single operation, substantially as described.

2. In a coupling, a draw-bar, a sleeve thereon having an apertured flange, a housing on the extension of the draw-bar, a spring-pressed pin in the housing adapted to be seated in the apertures of the flange, means for limiting the rotation of the draw-bar and arresting the 65 parts when the pin registers with one of the apertures, a flexible connection secured to the end of the pin, a shaft, a sheave-pulley for attachment with the flexible connection, substantially as described.

3. In a coupling, a draw-bar, a sleeve thereon having an apertured flange, a housing on the extension of the draw-bar, a spring-pressed pin in the housing adapted to be seated in the apertures of the flange, means for limiting the rotation of the draw-bar and arresting the 75 parts when the pin registers with one of the apertures, a flexible connection secured to the end of the pin, a shaft, a sheave-pulley for attachment with the flexible connection, 80 a guide on the extension through which the flexible connections operate, substantially as described.

4. In a coupler, an arrow-head coupler adapted to operate automatically, and a vertical-hook coupler adapted to be rotated into and out of vertical alinement with the arrow-head coupler, substantially as described.

5. In a coupler a guide having a rounded inner edge, a sleeve formed with the body of 90 the guide, a draw-bar arranged in the sleeve and having its protruding end bent at approximately right angles and terminating in a draw-head said draw-head acting in conjunction with the guide and arranged to partially rotate, substantially as described.

6. In combination with a body having a socket and an extension forming a guide, a coupler-head adapted to be rotated into and 100 out of operative position with relation to the guide, and an arrow-head coupler arranged below the first-named coupler and adapted to rest on a lower plane when out of operative position than it occupies when in operative position, substantially as described.

In testimony whereof I affix my signature in the presence of two witnesses.

GEORGE C. HARLIN.
